INVENTOR:
Richard A. Bates,
BY *J. H. Gibbs*
ATTORNEY.

UNITED STATES PATENT OFFICE.

RICHARD A. BATES, OF BERWICK, PENNSYLVANIA, ASSIGNOR TO AMERICAN CAR AND FOUNDRY COMPANY, OF NEW YORK, N. Y., A CORPORATION OF NEW JERSEY.

LUBRICATING DEVICE.

1,336,413.

Specification of Letters Patent. Patented Apr. 13, 1920.

Application filed November 4, 1919. Serial No. 335,690.

To all whom it may concern:

Be it known that I, RICHARD A. BATES, residing at Berwick, Columbia county, Pennsylvania, and being a citizen of the 5 United States, have invented certain new and useful Improvements in Lubricating Devices, of which the following is a full, clear, and exact description, such as will enable others skilled in the art to which it ap- 10 pertains to make and to use the same, reference being had to the accompanying drawings, which illustrate the preferred form of the invention, though it is to be understood that the invention is not limited to the ex- 15 act details of construction shown and described, as it is obvious that various modifications thereof within the scope of the claims will occur to persons skilled in the art.

20 In said drawings:

Figure 1 is a central longitudinal section of view taken through the lubricating device forming the subject matter of the present invention.

25 Fig. 2 is an inverted view of the structure shown in Fig. 1, that is looking from the interior of the lubricant chamber.

Fig. 3 is a transverse sectional view the section being taken on line 3—3 of Fig. 1.

30 Fig. 4 is a view taken partly in vertical section and partly in side elevation on the line 4—4 of Fig. 1.

Fig. 5 is a view taken on the same section as Fig. 1 with this difference that 35 whereas the parts are shown in assembled relation in Fig. 1 they are shown in Fig. 5 in the positions they occupy while the parts are being assembled for service.

The object of the invention is to provide 40 simple and economical means for lubricating surfaces and is especially adapted for use in mine car wheels, in which latter there is an oil reservoir adapted to hold a considerable quantity of lubricant.

45 Another object is to provide a device of the character described, which, due to the conformation of essential parts automatically locks itself in position where applied, thereby dispensing with the customary se- 50 cured threaded portions heretofore in vogue, which are separable in service due to vibration and from other causes. The device comprises but few simple and rugged parts which are economically produced and

are especially adapted to quantity produc- 55 tion.

Referring to the parts: 6 indicates a fragmentary portion of a mine car wheel or other receptacle adapted to contain lubricant in which a lubricating chamber indicated generally at 7 is formed therein. This body is perforated as shown and in the perforation is seated a plug 8 comprising a flanged head portion 9 equipped with a valve seat 10 and a hollow inwardly extending sleeve 11, which latter is formed with a plain exterior and relatively smooth surface as distinguished from a screw threaded exterior surface. The sleeve 11 is provided at diametrically opposite points 60 with seats 12 adapted to receive the bent locking end portions 13 of a locking yoke 14 hereinafter specifically described. In the present instance the seats 12 comprise slots extending entirely through the wall 65 of the sleeve 11 and the construction shown is the preferred construction in that when the parts are assembled as shown the device is automatically locked in position. The yoke 14 extends from the curved end portions 13 inwardly and the middle portion thereof is formed into a loop 15 of sufficient diameter to permit the passage therethrough of the stem 16 of the valve 17 and intermediate the head 18 of this valve and 70 the loop 15 an expansion spring 19 is interposed of such length that it normally seats 75 the head 18 of the valve as shown in Figs. 1 and 5, though it is possible to unseat this head as shown in Fig. 4 when it is desired 80 to fill the lubricant reservoir. In Fig. 4 a fragment of the spout 21 of an oil can is shown bearing against the exterior face of the head 18 for the purpose of unseating 85 the valve. Threaded upon the sleeve 11 and intermediate the flanged head 9 thereof and the body 6 is an annular packing 22, the purpose of which is to prevent waste of lubricant in service. In assembling the parts the valve is inserted from the rear 90 or bottom portion of the sleeve as shown after which the spring 19 is threaded upon the stem of the valve and the yoke 14 is applied to said stem whereupon the sleeve 95 may be projected through an orifice into 100 the lubricant reservoir and the parts are so proportioned that when the sleeve has been thus projected longitudinally a sufficient

distance the curved portions 13 of the yoke, which latter is of spring metal, will expand outwardly within the seats 12 and project beyond the exterior line of the sleeve sufficiently to interlock with the interior face 5 of the wheel or other body to be lubricated and the resiliency of the yoke member will hold the parts in coöperative engagement in which position the felt annulus 22 will perform its proper function.

Though the parts automatically interlock during assembly they are removable if desired and this is readily accomplished by merely driving the valve inwardly a sufficient distance to unseat the curved extension 13 of the yoke 14 whereupon said extensions 13 will be retained within the sleeve and the device may be removed. Preferably the sleeve 11 is of such external diameter 20 that a driving fit is secured between it and the member 6 and this plus engagement of the portions 13 with the interior face 6^a will effectually prevent accidental displacement and loss of the device in service.

25 What I claim is:

1. In a lubricating device a hollow flanged plug provided with seats intermediate its ends, a locking yoke held in said seats and forming a spring seat, a valve movable in 30 said spring seat and a spring on said spring seat adapted to actuate said valve.

2. In a lubricating device a hollow flanged plug provided with slots intermediate its ends, a locking yoke having curved end portions held in said slots said yoke forming a 35 spring seat, a valve movable in said plug and a spring on said yoke adapted to actuate said valve.

3. In a lubricating device a hollow plug 40 provided with a flange and with slots inter-

mediate its ends, a spring supporting yoke, having end portions adapted to coöperate with said flange to lock the plug in operative position, a valve and a spring adapted to seat said valve.

4. In a lubricating device a hollow flanged plug provided with seats intermediate its ends, a locking yoke held in said seats and forming a spring seat, a valve having a stem portion extending through said spring seat 50 and a spring on said spring seat adapted to actuate said valve.

5. In a lubricating device a hollow flanged plug provided with slots intermediate its ends, a locking yoke held in said slots and forming a locking means, a valve movable in said yoke and a spring held by said yoke adapted to actuate said valve.

6. In a lubricating device a hollow flanged plug provided with slots intermediate its ends, a locking yoke projecting through said slots the yoke having a loop forming a spring seat, a valve movable in said spring seat and a spring bearing on said spring seat and valve adapted to actuate said valve.

7. In a lubricating device a hollow flanged plug provided with seats intermediate its ends, a locking yoke having curved end portions projecting through and being held in said seats and a spring seat formed by said yoke intermediate its ends, a valve having a stem movable in said spring seat and a spring on said spring seat adapted to seat said valve.

In witness whereof I have hereunto set 75 my hand in the presence of two witnesses.

RICHARD A. BATES.
